UNITED STATES PATENT OFFICE

BRUNO REICHELT, OF NUTLEY, NEW JERSEY

SWEATBAND FOR HATS

Application filed October 4, 1928. Serial No. 310,378.

My present invention, in its broad aspect, has to do with improvements in means for preventing perspiration or sweat or other moisture or substance from penetrating the material of a hat and soiling the outside ribbon of the hat or discoloring the material of the hat. More especially it is my purpose to provide a device of this broad character which will prevent penetration of moisture through the thread or stitching holes and the like between the usual leather sweatband and the outer material of the hat and the outside ribbon; it is also designed to make the hat more comfortable upon the head, prevent dripping of perspiration down upon the face in hot weather, provide a more resilient and comfortable pad or support about the head of a wearer, and improve upon the method and means now in use for attaching the usual leather sweat band to the material of the hat. It also lends toward keeping and preserving the shape of the hat.

During the summer months it has been found that increased perspiration from the head finds its way through stitch or thread holes in the hat and discolors the outside ribbon and material of the hat. My device is designed not only to prevent penetration of perspiration or sweat through the stitch holes, but to absorb such perspiration as accumulates between the leather band and the felt thereby preventing perspiration and sweat from permeating the felt and entering the ribbon. My device consists in an elongated insertion or ribbon woven in one-piece to form a loop and opposed wings, one facing toward the head of the wearer and the other toward the inner surface of the hat. This is placed between the usual leather band and the hat with the narrower wing toward the leather band and the broader wing toward the hat. The narrow wing is stitched to the leather band and the broader wing to the hat, the band is partially waterproof (that is the loop portion is partially water proof) and partially capable of absorbing moisture— preferably that side of the loop toward the

leather band is capable of absorbing moisture. The device is also provided with means for retaining the fibre cord. If desired the material may be woven in two different types; one water proof and the other absorbent, i. e. a porous like fibre or texture.

Accordingly it will be seen that there is no direct communication of thread holes or stitch holes with the hat felt or material from the inner surface of the usual leather sweat band. The device also cushions the head, absorbs perspiration, more desirably mounts the usual leather hat band, and is otherwise desirable for use with summer or other hats.

Other objects and advantages of my sweat band for hats will become apparent as the description of my invention proceeds, but the scope of my invention is to be determined by reference to the claims appended hereunto.

In the drawings wherein is illustrated the preferred form of my invention;—

Figure 1 is a side view of a hat partly broken away to show the sweat band construction.

Figure 2 is an enlarged sectional detail of my device.

Figure 3 is an end section through my device.

Figure 4 is a perspective view of my device without a leather sweat band being attached thereto, and

Figure 5 is a view of my device with a felt or other absorbent liner placed in the loop and especially designed for use with ladies' hats where the material is very thin.

In the drawings wherein like characters of reference are used to designate like or similar parts throughout the several views;—

The numeral (1) designates a felt hat of conventional type such as a derby or soft felt hat, and which has a rim (2) and an outside decorative ribbon (3). Such hats are provided usually with a well known type of leather sweatband (4). However, in practice, the sweat band becomes permeated with perspiration which soaks through the felt and thread holes and soils the ribbon (3) and outside of the hat.

To prevent this, I provide an integrally

woven member having a relatively narrow wing (5) which is faced toward the inner surface of the leather sweat band (4) and stitched thereto as at (4a). The lower part of 5 my member has a tubular portion (6) through which the fibre cord (7) is trained, and the stitching (4a) is preferably above the portion (6). My member is thus attached to the leather band (4) by means of stitching extending into the wing (5). Another considerably broader wing (8) is attached by stitching (8a) to the inner surface of the hat itself as shown in Figure 1, and between the wing (5) and the wing (8) is a loop (9) having 10 an absorbent portion (10) facing the leather sweat band and a waterproof portion (10a) facing the inner surface of the hat. Accordingly since my device is placed between the usual leather sweatband and the inner surface 15 of the hat perspiration will be absorbed by portion (10) and prevented from entering the material of the hat and accordingly soiling the ribbon (3) by the moisture proof portion (10a); furthermore the leather band 20 is attached to wing (5) and the device itself including the leather band attached to the hat through wing (8) thus preventing moisture from following through the stitch or thread holes. My device also more perfectly pads 25 the hat where it engages the head, keeps the shape of the hat, more desirably mounts the leather band (4), and otherwise lends to the attainment of a better article of apparel. 30 With respect to ladies' hats which are somewhat lighter it may be desirable to place additional absorbent material (11) in the loop (9), such as is shown in Figure 5.

From the foregoing it is believed that the 35 construction and operation of my device is apparent, but special attention is called to its simplicity, durability, and the fact that it can be manufactured in quantities at relatively small cost.

I do not wish to be restricted to details of 40 size, proportion, form or specific construction of the several parts of my device except where such limitations are indicated in the claims, and obviously changes may be made in the constructions herein described without departing 45 from the spirit of the invention provided such changes fall within the scope of the appended claims.

I claim:

1. A device for use with hats comprising a 50 member adapted to be disposed between the hat and the sweat band thereof, said member having a looped portion one side of which is waterproof and the other absorbent of moisture, a wing formed on said member on one side of the loop and adapted to be attached to the hat, and another wing formed on the other side of the loop and adapted to be attached to the sweat band for supporting the same, and means for carrying a fibre cord.
2. A device for use in hats comprising a 55

fabric member with a loop and extensions or wings on either side of the loop, one portion of the loop is absorbent of moisture which is nearest the sweatband, and the other portion of the loop is waterproof which is nearest the hat, preventing the moisture from passing through the waterproof section, the said wings or extensions of the loop portions are adapted to be attached to the hat on one side and to the sweatband on the other side.

In testimony whereof, I affix my signature hereunto.
